UNITED STATES PATENT OFFICE.

CHARLES A. DEARBORN, OF NEW YORK, N. Y.

SEWING-MACHINE.

1,147,486.

Specification of Letters Patent. Patented July 20, 1915.

Application filed December 15, 1914. Serial No. 877,339.

To all whom it may concern:

Be it known that I, CHARLES A. DEARBORN, a citizen of the United States, residing in the borough of Manhattan, city, county, and State of New York, have invented certain new and useful Improvements in Sewing-Machines, of which the following is a full and clear specification.

The present invention is an improvement upon the machine covered by an application filed by me on October 7th, 1914, Serial No. 865,514, and in common with the machine of said application, has for its primary purpose the sewing of what are commonly known as "turned" seams, such as are formed upon the finished edges of coats and other garments.

In the preparation of a "turned" seam, as heretofore commonly practised, the tailor manipulates the seam edge of the work by bending and rolling it back and forth between his thumb and fingers, while pressing upon the seam to bring the turned seam outwardly as near as possible to the turned back edges of the upper and lower layers of cloth, and while holding the manipulated work he bastes it along the turned edges preparatory to the final stitching operation.

The machine of the present invention is designed to rapidly and accurately perform the same work as that heretofore done entirely by hand. In accomplishing the desired result, I provide a sewing machine having the customary stitch forming and feeding mechanisms with a pair of cloth engaging plates or fingers disposed so as to engage the work above and below, and provided with operating mechanism for rapidly reciprocating them transversely of the line of feed, while in engagement with the work to cause the upper and lower layers of the work to be rolled back and forth upon the turned seam and be gradually worked away from the seam which will be presented at the extreme edge of the turned upper and lower layers.

In the preferred embodiment of the invention, I have arranged the operating mechanism so as to impart to the cloth engaging plates or fingers, a plurality of quick reciprocating movements for each penetration of the needle in the sewing operation, the cloth being manipulated during the action of the feed as well as during the penetration of the needle.

In order that my invention may be fully understood I will first describe the same

with reference to the accompanying drawings, and afterward point out the novelty more particularly in the annexed claims.

In said drawings, Figure 1 is a front elevation of my improved sewing machine. Fig. 2 is a sectional plan view of the same. Fig. 3 is a detail end elevation, partly in section, of the same. Fig. 4 is an enlarged detail front elevation, partly in section, of the work manipulating jaws or fingers. Figs. 5 and 6 are detail sectional views of the same taken respectively on the section lines 5—5 and 6—6 of Fig. 4. Fig. 7 is an enlarged detail, horizontal, sectional view, and Fig. 8 is an enlarged detail, front elevation of the eccentric operating mechanism of said work manipulating jaws or fingers. Fig. 9 is a detail perspective view of a piece of work, such as performed by the improved machine. Fig. 10 is a detail view of a slight modification.

The machine is built upon any suitable frame, such as shown in which 1 is a base and 2 the usual sewing machine arm, extending up from the base. Journaled in the arm 2 and in the usual bearing standards upon the base 1, is the main shaft 5 which extends horizontally and longitudinally through the machine and is provided at one end with the fly wheel 6 and the main driving pulley 7. At the opposite end of the shaft 5 is mounted a rotary hook (not shown) of the ordinary stitch-forming mechanism, or, if preferred, the ordinary rotary shuttle of well known form may be suitably mounted upon the shaft 5.

10 is a common form of needle bar carrying the usual needle 11, operating in bearings 12 of the arm 2, and actuated by the usual rocker lever 13, journaled upon the arm 2 at 14, and driven by the eccentric link mechanism actuated by the eccentric 16 upon the shaft 5.

20 is a cloth supporting plate of any suitable design, rigidly mounted upon one of the bearing standards of the machine frame.

25 is the usual feed dog operating in the slots of the cloth supporting plate 20 and rigidly mounted at 26 upon the horizontal rocker arm 27, which is journaled upon bearing pin 28 carried in the upper end of the vertical rocker arm 29, which carries at its lower end the bearing pin 30 suitably journaled in the base frame of the machine. The forward and back movements of rocker arm 29 are effected by means of the eccen-

tric 35 upon shaft 5 and eccentric link 36 operating upon the eccentric 35 and pivoted at its opposite end upon the journal pin 28. Up and down movements of rocker arm 27 are effected by the cam 40 on shaft 5 and the arm 41 projecting from rocker arm 27 and resting upon the cam 40.

45 is the usual spring actuated presser foot mounted upon the vertical rod 46, which 10 has bearings in the sewing machine frame arm and is actuated and controlled to co-operate with the work supporting plate and feed dog in the usual manner.

The stitch-forming and feeding mechanisms above described are of the common construction in sewing machines in general use today. Their specific form is not essential to the present invention but they 15 are described only as illustrating the principles of the necessary elements of the improved machine, the novelty in which comprises the combination with suitable work feeding and stitch-forming mechanisms of devices for engaging the upper and lower 20 layers of work adjacent to a turned seam and manipulating the work to roll the layers back and forth upon the seam to cause 25 the seam to be brought as closely as possible into alinement with the turned edges of the 30 work.

50 is a forward section or extension of the cloth supporting plate mounted upon a bracket arm 51, which extends up from the base 1 of the machine frame. This plate 35 section 50 is separated from the main cloth supporting plate 20 to form a space in the plane of feed for the operation of the cloth manipulating plates or fingers which will now be described.

40 55 is a bracket horn projecting up from the base 1 of the machine frame between the feed plates 20 and 50 and upon the inner side of the line of feed. This bracket horn 55 has a head or enlargement 56, projecting 45 beneath the plane of feed. The forward face of the horn 55 and head 56 constitutes a guide surface for the transversely reciprocating cloth manipulating plates or 50 fingers.

50 and 61 are the cloth manipulating plates extending longitudinally of the machine at the front. These plates 60 and 61 are supported with their vertical faces adjacent to their jaw ends against the guide 55 front face of the horn 55 and head 56. The under plate 60 is formed at its outer end with a horizontal cloth engaging jaw 65, whose cloth engaging surface is ribbed or serrated as shown at 65^a. A horizontal slot 66 is cut through the jaw end of the plate 60 to receive an anti-friction roll 67 supported upon a pin 68 which is mounted in an opening 69 of the head 56. This plate 60 reciprocates transversely of the line of feed 65 upon the anti-friction roller 67.

A guide plate 70 shaped to correspond with the horn 55 and head 56 is secured to the horn and head by means of pins 68 and 75, the heads 68^a and 75^a of said pins engaging the guide plate 70 for holding it in place, and said pins entering the openings 69 of head 56 and 76 of horn 55 and being held therein by set screws 77 and 78. I prefer to employ the cylindrical pins 68 and 75 held by set screws 77 and 78 for securing the guide plate 70 in place, since by these means I am able to secure the plate 70 in the exact position desired for confining and guiding the plate 60 in proper position, without danger of binding it too closely against the plate. By these means there is less chance of an unskilled operator destroying the adjustment of the guiding plate 70 as would possibly happen were ordinary set screws employed for securing the plate 70 in place.

The cloth engaging plate 61 is formed at its free end with a horizontal jaw 62 which is presented above the plane of feed in operative relation to the under-jaw 65 of plate 90 60. The cloth engaging face of the jaw 62 is formed with ribs or serrations 62^a, similar to those of the jaw 65. The ribs or serrations of the two cloth engaging jaws extend approximately parallel with the line 95 of feed, but in some cases I have found it desirable to form them on a slight angle to the line of feed to give a slight stretching action to the upper and lower layers of cloth away from the line of seam during the 100 moments that the jaws are in engagement with the cloth, while the feed is taking place. This inclination of the ribs of the cloth engaging jaws to the line of feed is illustrated in Fig. 10 of the drawings.

80 is a limit pin formed with eccentric heads 81 and 82 at its inner and outer ends. The eccentric heads of this limit pin rest in the circular recess 83 of horn 55 and circular opening 84 of the guide plate 70, so 110 as to support the central bearing portion of the pin between horn 55 and plate 70 in position to engage the horizontal guide edge 63 of plate 61. The pin 80 supports the plate 61 in its reciprocating movements in 115 proper relation to the lower plate 60 when there is no work in the machine. The pin 81 has a niche 85 in its outer end by means of which it can be turned in its support to raise or lower the central bearing portion of the pin so as to present cloth engaging jaw 62 farther away or closer to the cloth engaging jaw 65. This adjustment is not essential but is useful from a manufacturing standpoint, since it provides a convenient means for setting the machine for different grades of work. It will be understood that a fixed limit pin set for the finest grade of work would answer the purpose.

The plates 60 and 61 have, adjacent to 130

their jaw ends, rearwardly presented lugs 90 and 91, which are connected by a contractile spring 95 which yieldingly holds the jaws 62 and 65 together, and allows the 5 upper jaw 62 to automatically adjust itself to suit the thickness of the work presented between the jaws.

The cloth manipulating plates 60 and 61 are provided at their inner ends with eccentric driving mechanism for imparting to them rapid reciprocating movements in opposite directions. The preferred form of such eccentric operating mechanism is illustrated in the drawings and shown in particular detail in Figs. 7 and 8. The plate 60 is formed at its inner end with an integral circular strap or ring 100, which rests upon a cylindrical collar 101 against an annular flange 102, to which it is secured by a 20 hexagonal nut 103, screwed upon the threaded portion 104 of the collar 101. This collar 101 encircles and operates upon an eccentric 105 secured to a shaft 106 freely journaled in the horizontal bearing 107 of 25 the machine frame. A pin 108 passes through the eccentric 105 and shaft 106 for securing the eccentric in place upon the shaft, the collar 101 extending over the pin 108, so as to prevent its accidental displacement. The collar 101 is held against displacement upon the eccentric 105 by an outer collar 110, mounted upon the end of shaft 30 106 and secured by a set screw 111.

Formed integrally with the eccentric 105 and offset therefrom diametrically, is a second eccentric 115, upon which is mounted a collar 116, formed with an annular flange 117 and secured upon this collar 116 is the strap or ring 120 formed integral with the 35 inner end of the upper cloth manipulating plate 61. A nut 121 confines the ring 120 against the flange 117 of collar 116. In assembling the eccentric operating mechanism just described, it will be observed that the 40 inner member is first mounted upon its eccentric, then the double eccentric is mounted upon the shaft and the outer member mounted upon its eccentric and the whole mechanism secured in place by the outer collar 110. In the rotation of the shaft 106 the connected eccentrics 105 and 115 rotate in the rings 100 and 120 of plates 60 and 61, to cause said plates to reciprocate in opposite directions. Shaft 106 carries at its rear 45 end a driving belt-pulley 125 to receive a belt driven by any suitable power.

It will be understood that the main driving pulley 7 and auxiliary driving pulley 125 are so proportioned with regard to the 50 power mechanism, that operates them, that the shaft 106 will be driven much more rapidly than the main shaft 5 of the machine. I have found in demonstrating my improved 55 machine, that excellent results are obtained by operating the shaft 106 about 8 times as

fast as the main shaft 5, since by this means an effective number of reciprocations of the cloth engaging jaw for each stitch, can be obtained.

In operating the improved machine for 70 producing a turned seam, it will be understood that the work having the original seam in place is presented in the machine with the upper and lower layers of cloth turned into approximately the desired position. The machine is started with the work engaged by the main feeding mechanism and by the cloth manipulating jaws. As the work is fed in to the machine, the jaws 75 62 and 65 rapidly move back and forth upon the upper and lower layers of cloth to effect a rolling of the work upon the seam. In practice I find it desirable to impart about 4 of these rolling movements during a feeding stroke and about 4 more of these rolling 80 movements during the penetration of the needle. This rolling of the material upon the seam causes the cloth to be spread away from the seam and brings the seam almost in line with the outer exposed folded edges 85 of the upper and lower layers in which position the work is held by the ordinary feeding mechanism while the stitches are made.

The machine of my present application is 90 designed for the same purpose as the machine of my application above referred to, Serial No. 865,514. There is a common principle involved in both machines in that both effect the spreading of the upper and lower layers of cloth away from the seam, so as to bring the seam as closely as possible to the folded edges of the layers of cloth. Aside from these features, however, which are common to both machines, there is an 95 important novel principle involved in the machine of my present application, in that the cloth engaging members of the present machine effect a rolling of the work upon the turned seam for effecting the desired 100 result.

I claim:

1. In a sewing machine for stitching turned seams, the combination with suitable work feeding mechanism, and suitable stitch forming mechanism, of means adapted to engage the turned layers of material and roll each of said layers back and forth upon the seam line, in opposite directions for the purpose set forth.

115

2. In a sewing machine for stitching turned seams, the combination with suitable work feeding mechanism, and suitable stitch forming mechanism, of means adapted to engage the turned layers of material above and below the plane of feed and roll them oppositely back and forth upon the seam line transversely of the direction of feed for the purpose set forth.

120

3. In a sewing machine for stitching turned seams, the combination with suitable 130

125

- work feeding mechanism, and suitable stitch forming mechanism, of means adapted to engage the turned layers of material above and below and roll the same back and forth 5 upon the seam line in opposite directions during the feeding operation.
4. In a sewing machine for stitching turned seams, the combination with suitable work feeding mechanism, and suitable stitch forming mechanism, of means adapted to engage the turned layers of material above and below and roll the turned layers back and forth upon the seam line in opposite directions during the operation of the stitch-forming mechanism.
5. In a sewing machine for stitching turned seams, the combination with suitable work feeding mechanism and suitable stitch forming mechanism, of a pair of oppositely 20 acting cloth engaging members engaging the work above and below the plane of feed adjacent to the seam line and means for reciprocating said members transversely of the line of feed in opposed directions.
- 25 6. In a sewing machine for stitching turned seams, the combination with suitable work feeding mechanism and suitable stitch forming mechanism, of a pair of oppositely acting cloth engaging members engaging the work above and below the plane of feed adjacent to the seam line, means for relatively adjusting said members, and means for operating said members in opposed directions.
- 30 7. In a sewing machine for stitching turned seams, the combination with suitable work feeding mechanism, and suitable stitch forming mechanism, of a pair of cloth engaging members movable transversely of the line of feed and engaging the work above 35 and below the plane of feed, yielding means maintaining the operative relation of said cloth engaging members, and operating means for oppositely reciprocating said cloth engaging members in opposite directions.
- 40 8. In a sewing machine for stitching turned seams, the combination with suitable work feeding mechanism, and suitable stitch forming mechanism, of a pair of cloth engaging members movable transversely of the line of feed and engaging the work above 45 and below the plane of feed, a spring yielding means maintaining the operative relation of said cloth engaging members, means for relatively adjusting said members, and operating means for oppositely reciprocating said cloth engaging members to roll the work back and forth upon the seam line.
- 45 9. In a sewing machine for stitching turned seams, the combination with suitable work feeding mechanism and suitable stitch forming mechanism, of a pair of cloth engaging jaws having ribbed faces adapted to engage the work above and below the plane 60 of feed, means for guiding said jaws, and means for reciprocating said jaws transversely of the line of feed in opposed directions.
10. In a sewing machine for stitching turned seams, the combination with suitable work feeding mechanism and suitable stitch forming mechanism, of a guiding horn arranged adjacent to the line of feed, a pair of cloth engaging plates operating in contact with said guiding horn, and formed with cloth engaging jaws, means for confining said plates upon said horn, and means for reciprocating said plates in opposite directions.
11. In a sewing machine for stitching turned seams, the combination with a suitable frame, work feeding mechanism, and stitch forming mechanism, of a guiding horn projecting from said frame adjacent to the line of feed, a lower cloth engaging plate formed with a work engaging jaw, a guide upon said horn engaging said lower plate for supporting its jaw beneath the plane of feed, an upper cloth engaging plate formed with a jaw, a guide upon said horn engaging said upper plate for presenting the jaw of the upper plate in operative relation to the jaw of the lower plate, a spring acting upon said upper plate for yieldingly holding it in position, and means for reciprocating said plates in opposite directions.
12. In a sewing machine, the combination with a suitable frame, work feeding mechanism and stitch forming mechanism, of a guide horn mounted upon said frame adjacent to the line of feed, a pair of cloth engaging members guiding upon said horn and adapted to engage the work above and below the plane of feed, a guide plate removably attached to said horn for confining said members in operative position, means for relatively adjusting said cloth engaging members, and means for operating said members.
13. In a sewing machine for stitching turned seams, the combination with a suitable frame, work feeding mechanism, and stitch forming mechanism, of a pair of cloth engaging plates movable transversely of the line of feed and engaging the work above 110 and below the plane of feed, a guiding horn mounted upon said frame for supporting said members adjacent to the work, and eccentric driving mechanism acting upon said members for reciprocating them in engagement with the work.
14. In a sewing machine for stitching turned seams, the combination with suitable work feeding mechanism and suitable stitch forming mechanism, of a pair of cloth-engaging jaws movable transversely of the line of feed and engaging the work above and below the plane of feed, said jaws being formed with ribs or serrations extending at an angle to the direction of feed, and means 125 for reciprocating said jaws transversely of the line of feed in opposed directions.

for reciprocating said jaws in engagement with the work.

15. In a sewing machine for stitching turned seams, the combination with suitable work feeding mechanism and suitable stitch forming mechanism, of a pair of transversely reciprocating plates having cloth engaging jaws arranged to engage the work above and below the plane of feed, a spring 10 yieldingly holding said jaws in operative relation, an adjustable guide pin engaging one of said jaws for determining its operative position, said pin being formed with eccentric ends resting in sockets in the machine frame and means for operating said plates.

16. In a sewing machine for stitching turned seams, the combination with suitable work feeding mechanism and suitable stitch

forming mechanism, of a pair of oppositely acting cloth engaging members movable 20 transversely of the line of feed and engaging the work above and below the plane of feed, a main operating mechanism for the work feeding mechanism and stitch forming mechanism, and an auxiliary operating 25 mechanism for said cloth engaging members, said main and auxiliary operating mechanisms being arranged to impart a plurality of active movements to the cloth engaging members for each complete feeding and 30 stitch forming operation.
